UNITED STATES PATENT OFFICE.

JOHN CHAMBERLIN, OF LONDON, ENGLAND.

CONTROLLED LEVER-FEED FOR MACHINE-TOOLS.

1,311,947.

Specification of Letters Patent.

Patented Aug. 5, 1919.

Application filed August 5, 1918. Serial No. 248,454.

To all whom it may concern:

Be it known that I, JOHN CHAMBERLIN, a subject of the King of Great Britain, residing at London, England, have invented 5 certain new and useful Improvements in Controlled Lever-Feeds for Machine-Tools, of which the following is a specification.

The object of the present invention is to provide a controlled lever feed for drilling 10 machines, capstan lathes, and the like by which an excessive rate of feed of the tool is resisted with the object of preventing or minimizing breakage of the tool by excessive feed, breakage usually also involving 15 damage to the work and much loss of labor in removing the broken tool.

To this end a retarding device is provided which is so inter-related with the lever feed that the advance of the tool is effected 20 against the action of the retarding device, the retardation being constant with a constant feed but varying in accordance with the increase or decrease of the rate of speed. At the normal speed the retardation is ordinarily such as not to appreciably add to the 25 resistance of the tool.

A further object of the present invention is to enable the tool at any stage of the feed to be withdrawn from the work for 30 clearing without hindrance from the retarding means, and thereafter to prevent the resumption of the control of the lever feed until the tool again makes contact at the point up to which it had previously traveled.

35 In the hereinafter described preferred embodiment of the present invention the controlled lever feed comprises a hydraulic cylinder and piston which is so interrelated with the lever feed that advance of the drill 40 or other tool must be accompanied by a simultaneous movement of the piston against the resistance offered by the oil or other fluid within the cylinder being forced from one side of the piston to the other through 45 a restricted passage which is preferably controlled by an adjustable valve.

In order that the piston shall not be actuated until the tool makes contact with the work, the operative connections between the 50 lever feed and the piston are made so as to allow the lever feed to bring the tool up to contact, or nearly up to contact, before the piston is actuated. Similarly, when withdrawing the tool, the lever feed is free to 55 bring the tool clear of the work without imparting any reverse movement to the piston,

which remains stationary for resuming control when the tool is again advanced up to contact.

The invention is illustrated in the accompanying drawings which show two preferred constructions.

Figure 1 is a detail view of the lever feed of a vertical drilling machine, having the present invention applied.

Fig. 2 is a view showing the lever feed of a horizontal drilling machine.

Figs. 3 and 4 are detail views of the operative connections.

Fig. 5 is a diagrammatic illustration of 70 the adjustable piston valve.

In Figs. 1, 3 and 4 a convenient and advantageous mode of operatively connecting the lever feed of a vertical drilling machine with the retarding device or check, is shown 75 the cylinder *a* being pivotally attached to the sliding bracket *b* of the machine slide *c*. The piston rod *d* is linked to a bolt *e* which is screwed into the end of the drill feed boss *f* to form an axial extension of the boss. 80 The link *g* is arranged to rotate freely on a bush *h* on the bolt, which bush serves to put clamping pressure on a pair of washers or disks *i* to clamp these to the boss *f* so as to rotate therewith, the clamping pressure 85 being applied by the head of the bolt *e* when the bolt is tightened.

The washers have short radial arms *k* and *k'* provided with side projections *l* and *l'* to make contact with opposite sides of 90 the link *g*. By appropriate adjustment of the washers *i*, the side projections *l* and *l'* are so set that, first, the projection *l* which is to actuate the link *g* on the advance of the drill does not contact with the link 95 until the drill is brought up to contact with the work or nearly so. Thereafter the projection *l* pushes the link *g* which in turn actuates the piston *m*. Secondly the projection *l'* on the other side of the link *g* is so set that the drill can be withdrawn out of the work sufficiently for clearing chips without the projection *l'* making contact with the link *g*, thus leaving the piston *m* stationary, and enabling the drill to be re-100 advanced at any speed back to the previous stage in advance at which the projection *l* will again make contact with the link *g*, and bring the control again into action. When however the feed lever *n* is returned to starting or off position, the projection *l'* gives 105 that range of movement to the link which

shall in turn bring the piston *m* back to its original position. On this return stroke of the piston the fluid is allowed by a suitable valve *o* to pass freely through the piston *m*.

5 An alternative method particularly suited for a capstan lathe or horizontal drilling machines is shown in Fig. 2 and comprises a pivoted sleeve *p* fixed intermediately of the ends of the hand operating lever *n'*, 10 through which sleeve is passed the free end of the piston rod *d*, suitably extended in length. On the piston rod *d*, and on opposite sides of the sleeve *p*, are adjustable stops *t*² which are set to allow the feed lever 15 to have movement independently of the control and to connect it with the control as hereinbefore described.

As shown in Fig. 5, the flow of fluid through the piston *m* may be controlled as 20 desired by causing the apertures *o'* in the valve *o* to register more or less with the openings *m'* in the piston *m*, the adjustment being effected by slackening the nut *r* on the end of the piston rod *d*.

25 While I have described in the foregoing specification the construction of parts and operations preferred, I am aware that numerous changes of construction and operation may be made without departing from 30 the spirit and scope of the invention, and I, therefore, do not wish to be understood as limiting myself by the positive terms employed in connection with the description except such as the state of the art may require.

35 What I claim is:—

1. A controlled lever feed for machine tools comprising in combination a feed lever, a retarding device, connecting means therebetween, means operated by the feed lever to 40 actuate said retarding device, and setting means for controlling the actuation of the retarding device whereby the said retarding device does not become operative until the 45 tool has been brought into or nearly into contact with the work, for the purpose described.

Copies of this patent may be obtained for five cents each, by addressing the "Commissioner of Patents, Washington, D. C."

2. A controlled lever feed for machine tools comprising in combination a feed lever, a retarding device, connecting means therebetween, means operated by the feed lever to 50 actuate said retarding device, and setting means for controlling the actuation of the retarding device, whereby the said retarding device is not operative during partial withdrawal of the tool for the purpose described. 55

3. A controlled lever feed for machine tools comprising in combination a feed lever, a movable member, a hydraulic cylinder, a piston therein, a valve control, a connection between said piston and said movable member, and setting means intermediate of the feed lever and hydraulic cylinder, said movable member being adapted to be coupled to the feed lever for movement through said setting means, substantially as and for the 60 purposes described.

4. A controlled lever feed for machine tools comprising in combination a feed lever, a movable member, a hydraulic cylinder, a piston therein, a valve in said piston, a connection between said piston and said movable member, and setting means intermediate of the feed lever and hydraulic cylinder, said movable member being adapted to be 70 coupled to the feed lever for movement through said setting means, substantially as and for the purposes described.

5. A controlled lever feed for machine tools comprising in combination a feed lever, a movable member, a hydraulic cylinder, a piston therein, a regulated valve in said piston, a connection between said piston and said movable member, and setting means intermediate of the feed lever and hydraulic cylinder, said movable member being adapted to be 80 coupled to the feed lever for movement through said setting means, substantially as and for the purposes described. 85

In testimony whereof, I affix my signature.

JOHN CHAMBERLIN.
